[57] CLAIM

A new original design for expandible cyclone stove, as
shown and described herein.

DESCRIPTION

FIG. 1 is a perspective view of an expandible cyclone
stove showing my new design;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a top plan view thereof;

FIG. 7 is a bottom plan view thereof; and,

FIG. 8 is a perspective view of a second embodiment
thereof, the only difference residing in the top two
buttons.
